Cornelius L. Ehrst
his ATTORNEY.

UNITED STATES PATENT OFFICE.

FREDERICK A. KOLSTER, OF WASHINGTON, DISTRICT OF COLUMBIA, ASSIGNOR OF
ONE-THIRD TO CORNELIUS D. EHRET, OF PHILADELPHIA, PENNSYLVANIA.

RADIO RECEIVING METHOD AND APPARATUS.

Application filed November 26, 1920. Serial No. 426,504.

To all whom it may concern:

Be it known that I, FREDERICK A. KOLSTER, a citizen of the United States, residing at Washington, District of Columbia, have 5 invented new and useful Radio Receiving Methods and Apparatus, of which the following is a specification.

My invention relates to a method of and apparatus for receiving signals represented 10 in transmission by undamped electro-radiant energy waves.

In accordance with my invention, undamped signal waves are received and made audible in a telephone receiver or the like by 15 employment of a source of fluctuating or alternating current of audible frequency, the telephone being coupled to the circuits of integrating, rectifying or equivalent detectors, the couplings and circuit arrangements being such that when no signal is being received there is no response by the telephone, and when a signal is received, energy 20 from the source of fluctuating or alternating current affects the telephone receiver to produce an audible response.

My invention resides in the method and apparatus hereinafter described and claimed.

For an illustration of some of the forms my invention may take, reference is to be 30 had to the accompanying drawing, in which:

Fig. 1 is a diagrammatic view of receiving apparatus embodying my invention and suitable for carrying out my method.

Fig. 2 is a diagrammatic view of a modification.

Referring to Fig. 1, R is a receiving antenna or other absorbing structure which, in the example illustrated, is connected to earth or counter-capacity E through the tuning inductance L and the primary P of an oscillation transformer whose secondary S is included in a circuit tuned by the variable condenser C. It is preferred that the secondary S, particularly when the detector structure is of the thermionic or audion type, shall have very high inductance so that the potentials of its opposite ends at any in-

stant shall be widely different. Therefore, when the inductance of the secondary S is great, as preferred, the capacity of the condenser C will be relatively small. Detecting means or equivalent, as audions or thermionic devices A and A¹, are related to the opposite ends of the inductance or secondary S.

The audion A comprises the plate or anode a, the grid g and the electron-emitting body or incandescent filament f, the latter traversed by current from the battery b, the magnitude of the filament current being adjustable by the variable resistance c. The grid g is connected through the grid condenser K with one terminal of the secondary S, a high resistance d connected to the grid g and filament f serving as a grid leak.

The parts of the audion A¹ and associated connections are similar to those described in connection with device A. One terminal of the grid g¹ is connected through grid condenser K¹ with the opposite terminal of the secondary S, and there may be employed a grid leak d¹.

The battery B is common to the anode circuits of the audions A, A¹, there being connected in the anode circuit of the audion A the primary p of a transformer whose secondary is s; and in the anode circuit of the audion A¹ is connected the primary p¹ of a transformer whose secondary is s¹. The secondaries s and s¹ are connected in series with each other and with the telephone receiver T.

Common to the anode circuits of the audions is the secondary s² of an audio frequency transformer in circuit with whence primary p² is any suitable source S¹ of fluctuating or alternating current of frequency equal to or corresponding with the frequency of the note which it is desired shall be produced in the telephone T.

When no signal is being received, the source S¹ will cause impression upon the circuit of the telephone T of a current which would produce a response thereby if it were

not for the fact that the couplings p , s and p^1 , s^1 produced, by suitable winding or mode of connection, equal and opposite effects upon the circuit of the telephone T. Accordingly, when no signal is being received, the source S^1 has no effect upon the telephone T.

When, however, undamped signal waves are received, the circuit S C being attuned thereto, as well as the antenna circuit, opposite ends of the inductance or secondary S will attain widely different potentials, the potential of the grid g rising, for example, while the potential of the grid g^1 falls. The current in one anode circuit therefore greatly increases while the other greatly diminishes, and accordingly the net effect of the couplings p , s and p^1 , s^1 is no longer zero, and there is transferred to the circuit of the telephone T current which causes its response evidenced by the production of a sound whose frequency is equal to or corresponds with the frequency of the current delivered by the source S^1 .

In Fig. 2 the arrangement is substantially the same as that in Fig. 1, except that the anode circuits of the audions A and A^1 are separate and distinct, and the source S^1 is coupled to both anode circuits through the transformers t , t^1 . In this case, however, the action is similar to that described in connection with Fig. 1 in that when no signal is being received there is no response by the telephone T, and when a signal is received, the telephone T produces a note whose frequency is equal to or corresponds with the frequency of the current delivered by the source S^1 .

As well understood in the radio art, the received energy of radio frequency may be amplified, as by a plurality of stages of radio frequency thermionic amplifiers, whose output circuit is coupled to the above mentioned inductance or secondary S. Similarly, the coupling secondaries s and s^1 may deliver to the input circuit of audio frequency amplifying apparatus, as a plurality of stages of audio frequency thermionic amplifiers, in whose output circuit the telephone T may be connected.

What I claim is:

1. The method of rendering undamped waves of radio frequency intelligible as signals of audio frequency independent of the frequency of said waves, which consists in subjecting detector input circuits to the received energy, subjecting the output circuits to a source of current of audible frequency, and subjecting a signal translating instrument to equal and opposite effects of said output circuits when no signal is received and to a current, when a signal is received, of frequency independent of the frequency of the received waves and corresponding with the frequency of said source of current.

2. Apparatus for rendering undamped waves of radio frequency intelligible as signals of audio frequency independent of the frequency of said waves comprising a plurality of devices having input and output circuits, means for subjecting the input circuits to the received energy, a signal translating instrument having equal and opposite couplings to the output circuits when no signal is received, and a source of current of audible frequency associated with the output circuits.

3. Apparatus for rendering undamped waves of radio frequency intelligible as signals of audio frequency independent of the frequency of said waves comprising a plurality of thermionic devices each comprising an anode, cathode and grid, means for changing the potentials of said grids in opposite senses by received energy, a signal translating instrument, a coupling between the same and each of the anode circuits, and a source of current of audible frequency associated with the anode circuits, said couplings producing equal and opposite effects upon said signal translating instrument when no signal is received and effecting in the circuit of said signal translating instrument when a signal is received a current of frequency independent of the frequency of said waves and corresponding with the frequency of said source.

4. Apparatus for rendering undamped waves of radio frequency intelligible as signals of audio frequency independent of the frequency of said waves comprising a plurality of thermionic devices each comprising an anode, cathode and grid, means for changing the potentials of said grids in opposite senses by received energy, a signal translating instrument, a coupling between the same and each of the anode circuits, and a source of current of audible frequency associated with the anode circuits, said couplings producing equal and opposite effects upon said signal translating instrument when no signal is received and effecting in the circuit of said signal translating instrument when a signal is received a current of frequency independent of the frequency of said waves and corresponding with the frequency of said source, said anode circuits being in part in common.

5. Apparatus for rendering undamped waves of radio frequency intelligible as signals of audio frequency independent of the frequency of said waves comprising a plurality of thermionic devices each comprising an anode, cathode and grid, a tuned circuit comprising inductance and capacity, the inductance of said circuit being relatively large with respect to the capacity, connections from said grids to opposite terminals of said inductance, a signal translating instrument, couplings between the same and

the anode circuits of said thermionic devices, and a source of current of audible frequency associated with said thermionic devices, said couplings producing equal and opposite effects upon said signal translating instrument when no signal is received and producing therein when a signal is received a current of frequency independent of the frequency of said waves and corresponding with the frequency of said source. 10

In testimony whereof I have hereunto affixed my signature this 26th day of November, 1920.

FREDERICK A. KOLSTER.
